(57) **CLAIM**

The ornamental design for a wall panel, as shown and described.

DESCRIPTION

1. Wall panel
- 1.1 : Partially enlarged perspective view 1
- 1.2 : Partially enlarged perspective view 2
- 1.3 : Partially enlarged front view 1
- 1.4 : Partially enlarged front view 2
- 1.5 : Partially enlarged front view 3
- 1.6 : Partially enlarged front view 4
- 1.7 : Front
- 1.8 : Back
- 1.9 : Left
- 1.10 : Right
- 1.11 : Top
- 1.12 : Bottom
- 1.13 : Reference view 1
- 1.14 : Reference view 2
- 1.15 : Reference view 3

The present article is a wall panel which may be used as an interior wall material or an exterior wall material; the present article may be designed as a plurality of wall panels installed horizontally as shown in reference views 1 and 2, for example, and may also be designed as a plurality of wall panels installed vertically as shown in Reference view 3, for example; reproductions 1.13, 1.14, and 1.15 are reference views showing the state in use of the claimed design and form no part thereof.

1 Claim, 15 Drawing Sheets
